UNITED STATES PATENT OFFICE.

JOHN RUMERY, OF CLEVELAND, OHIO.

WINDOW-LOCK.

1,185,829.

Specification of Letters Patent.

Patented June 6, 1916.

Application filed February 8, 1915. Serial No. 6,736.

To all whom it may concern:

Be it known that I, JOHN RUMERY, a citizen of the United States, residing at Cleveland, in the county of Cuyahoga and State 5 of Ohio, have invented certain new and useful Improvements in Window-Locks, of which the following is a specification.

This invention has reference to window locks, all substantially as shown and described and particularly pointed out in the 10 claim.

In the accompanying drawings, Figure 1 is a plan view of the invention in working position on a window and showing the windows unlocked. Fig. 2 is a like view to Fig. 1 but showing the windows locked. Fig. 3 is a sectional elevation on line 3—3, Fig. 1, looking to the left. Fig. 4 is a sectional view on line 4—4, Fig. 2. Fig. 5 is a 20 side elevation of one of the dogs and cross section of the cam.

The idea herein is to have a lock which will prevent the lower sash being raised and the upper sash being lowered beyond certain predetermined positions, and further that both locks should be under the same control and alike effective in locking the sashes with means that cannot be tampered with from without and will be effective in 30 holding the windows against a forced entrance.

To these ends I employ two locking studs or dogs 2 and 3 which may be of cast metal as shown, or struck up from suitable sheet 35 metal. These dogs are alike and interchangeable and are shown as pivoted between ears 5 in a sheet metal base 6 adapted to be seated and fixed on the top of the lower sash in the left hand corner, in this instance.

40 The said dogs are also provided with heels h which extend inward at substantially right angles to the body thereof from the pivot 4 and are tapered on their back substantially as shown, so as to deepen toward 45 the pivot. The relation of said dogs on the base 6 is at right angles to each other, and said base has a hole in its middle portion adapted to receive a screw 7 which helps to fasten the base on the lower sash S and 50 serves also as a pivot for the horizontally rotatable cam C. The said cam also is preferably struck up from sheet metal and has a counter sunk middle portion or boss at its center resting on said plate and of such deviation as will bring the edge of the cam

over the heels h of the said dogs. The working edge of the cam lies between the two stops 8 thereon, at opposite sides respectively and adapted in one instance to be turned against dog 2 and in the other 60 against dog 3, or the ears carrying the same, according as said dogs are to be brought into engaging or disengaging position.

For engaging or locking purposes I provide plates 10 and 11 for the window casing and the upper sash respectively. These plates have occasional holes or openings 12 for engagement by the said dogs and the plates are laid flush into their supports to afford the usual smooth surfaces for the 70 sashes. The play of the dogs in and out on their pivots is just sufficient to permit engagement in said slots or openings 12 in one instance and to retire them from such engagement when the sashes are to be liberated. The cam edge between the two stops 8 provides for this difference in conjunction with the taper or incline on the heels h of the dogs in conjunction with springs 15 wound about the pivots of the dogs and 75 adapted to throw them out into the locking openings 12 when the cam recedes from said heels as in Figs. 2 and 4. Thus, the said cam edge is deepest at d and narrowest at d' , these terms being used in respect to the 80 pivot 6. In fact the edge portion d is cut back farther than d' sufficiently to give the dogs free outward swing into locking position under the action of their springs 15 while the edge portion d is sufficiently 85 deeper to ride upon the said heels in their heavier base portions and thus forcibly throw the dogs back to at least upright position and withdraw them entirely from the plates 10 and 11. Both portions d and d' 90 of the cam have sufficient depth to lie across both the heels h at the same time. Figs. 1 and 3 show the dogs in retired position and Figs. 2 and 4 in locking position and the handle 16 on the cam serves to rotate it to 95 either position.

Each flaring opening 12 in the plates 10 and 11 provides sufficient clearance at its upper rounded end to admit the dog freely, and the inclined straight sides at the lower 105 end of the slot engage the side edges of the spring-pressed dogs and keep the window from rattling.

What I claim is:

A lock as described having two dogs piv- 110

oted at right angles to each other and having projections behind their pivots tapered inward and downward on their upper surface, in combination with a flat substantially 5 disk-shaped cam having a pivot approximately at its middle and an edge portion of varying depths from said pivot adapted to be brought over said projections successively and change the positions of said dogs,

and said edge portion having opposite stops 10 at its ends.

In testimony whereof I affix my signature in presence of two witnesses.

JOHN RUMERY.

Witnesses:

R. B. MOSER,
GEO. E. KRICKER.
